(57) **CLAIM**

The ornamental design for a convertible tote bag assembly, as shown and described.

DESCRIPTION

FIG. 1 is a perspective view of a convertible tote bag assembly;

FIG. 2 is a front elevation view thereof;

FIG. 3 is a rear elevation view thereof;

FIG. 4 is a left side elevation view thereof, the right side being a mirror image thereof;

FIG. 5 is a top plane view thereof; and,

FIG. 6 is a bottom plane view thereof.

The body of the model in FIG. 1 is shown in broken lines for illustrative purposes only and forms no part of the claimed design.
